(57) **CLAIM**

The ornamental design for a combined digital disc player and navigation system for a vehicle, as shown and described.

DESCRIPTION

FIG. 1 is a perspective view of a combined digital disc player and navigation system for a vehicle, showing our new design;

FIG. 2 is a perspective view showing the display opening thereof;

FIG. 3 is a front view of FIG. 1;

FIG. 4 is a left side view thereof;

FIG. 5 is a right side view thereof;

FIG. 6 is a top plan view thereof;

FIG. 7 is a bottom plan view thereof;

FIG. 8 is a front view showing the display opening thereof;

FIG. 9 is a rear view showing the display opening thereof;

FIG. 10 is a left side view showing the display opening thereof;

FIG. 11 is a right side view showing the display opening thereof;

FIG. 12 is a top plan view showing the display opening thereof; and,

FIG. 13 is a bottom plan view showing the display opening thereof.

The broken line shown in FIGS. 1 to 13 is for illustrative purposes only and forms no part of the claimed design.

1 Claim, 6 Drawing Sheets
